UNITED STATES PATENT OFFICE.

ZACHARIAH WEBB ONIONS, OF WAINFELIN, PONTYPOOL, ENGLAND.

ROLLING-MILL.

SPECIFICATION forming part of Letters Patent No. 694,025, dated February 25, 1902.

Application filed June 25, 1901. Serial No. 65,917. (No model.)

To all whom it may concern:

Be it known that I, ZACHARIAH WEBB ONIONS, a subject of the King of Great Britain, residing at Wainfelin, Pontypool, in the county of Monmouth, England, have invented new and useful Improvements in Rolling-Mills, (for which I have made application for patent in Great Britain under No. 7,755, bearing date April 16, 1901,) of which the following is a specification.

My invention relates primarily to that class of rolling-mills now known as "continuous" mills, in which the piece of metal being rolled passes on through a series of successive rolls 15 in front of each other without the intervention of manual labor. In such mills, where all the rolls have their axes in the same plane, it is found necessary to provide means by which the piece during its travel from the 20 pass in the one pair of rolls to the pass in the next pair of rolls shall be turned over at right angles, so that the fin formed at the joint-surface of the one pair of rolls shall fall in or about the solid bottom of the pass of the succeeding pair of rolls. Also the difficulty of 25 turning over the piece between two pairs of rolls has been avoided by having the axes of each succeeding pair of rolls placed transversely to those of the preceding pair. Such 30 an arrangement, however, is open to many objections.

Now the object of this my invention is to provide an improved arrangement of rolls whose axes are all parallel to each other and so disposed that the piece of metal being rolled may 35 pass on from rolls to rolls without the necessity of being turned over. I attain this object by the mechanism illustrated in the accompanying drawings, in which—

40 Figure 1 is a side view of two pairs of rolls arranged according to this my invention. Fig. 2 is a front view of my invention, showing a leading pair of rolls. Fig. 3 is a front view of my invention, showing a succeeding pair of rolls to receive the piece from the previous 45 pair.

Similar numbers refer to similar parts throughout the several views.

Two pairs of rolls only are shown on the 50 drawings; but any required number may be used. The rolls have their axes in the horizontal plane and are all parallel to each other, rolls 5 and 6 forming one pair and rolls 7 and 8 forming a succeeding pair. In each roll an

inclined surface 9 is provided to agree with 55 each other as a pair and at an angle of forty-five degrees, or thereabout. It will be seen that to provide these surfaces 9 the enlarged diameters or collars 14, 15, 16, 17, 18, and 19 are provided, which are made to fit into and 60 agree with deepened grooves 20, 21, 22, 23, 24, and 25 in the respective opposite rolls, by which means the two rolls are firmly held to each other in an axial direction to resist end movement when in operation. More than 65 one of such pair of inclined surfaces may be used in the same pair of rolls, two of such being illustrated. In these surfaces the passes 10, 11, 12, and 13 are made, and it will be noticed that the finning-joint in pass 10 is 70 at right angles to the finning-joint in the succeeding pass 12. The disposition of the pass in each succeeding pair of rolls is thus alternated, so that the fin from one pair is made to avoid the finning-joint in the succeeding 75 pair. It will therefore be obvious that by means of a suitable guide to convey the piece from one pair of rolls to the next the piece may pass on throughout a given series without any turning over or further attention. I 80 have illustrated the passes as of a somewhat diamond shape as being most convenient for explanation; but such sectional shapes will be varied to suit requirements. The rolls may be driven and adjusted by any of the 85 well-known suitable means. Two or more of such continuous pairs of rolls may be used as a complete mill or in conjunction with other forms of finishing-mills, according to sections of rolled material required.

I am aware that continuous trains of rolls have already been made whose successive passes have been axially disposed in opposite inclined directions, and therefore I do not claim such broadly; but

90 What I claim, and desire to secure by Letters Patent, is—

In a continuous-roll train having upper and lower rolls whose passes are successively placed axially in opposing inclined positions, 100 such passes having the initial inclined surfaces 9 as shown on the drawings and for the purposes specified.

ZACHARIAH WEBB ONIONS.
